UNITED STATES PATENT OFFICE.

SIGMUND L. LEDERER, OF PROVIDENCE, RHODE ISLAND.

DESIGN FOR AN ORNAMENTAL CHAIN.

SPECIFICATION forming part of Design No. 12,794, dated February 28, 1882.

Application filed December 22, 1881. Term of patent 7 years.

To all whom it may concern:

Be it known that I, SIGMUND L. LEDERER, a citizen of the United States, residing at Providence, in the county of Providence and State of Rhode Island, have invented and produced a new and original Design for Ornamental Chains, of which the following is a full, clear, and exact description, reference being had to the accompanying drawings, forming part of 5 this specification.

Figure 1 is a perspective view of an ornamental four-sided sleeve, representing on each side the block letter H. It is formed of a short piece of square tubing, cross-cut at each end, 15 so as to represent on each of the four sides the letter H. These short square letter-H sleeves are connected with the links of an ornamental chain in various ways, and form the leading feature of my new design. Fig. 2 is a perspective view, showing links of an ornamental chain united by means of the letter-H sleeves shown in Fig. 1. Fig. 3 is a perspective view, showing a link for an ornamental chain, ornamented by inserting three of the letter-H sleeves. Fig. 4 is a perspective view of a twisted chain-link, ornamented by inserting two letter-H sleeves. Fig. 5 is a perspective view of a chain-link, showing one of the letter-H sleeves inserted between the loops of the link. 25 In the drawings, *a* is a short piece of square tube, into the ends of which the cuts *b b* are made. When so cut the short piece of tube represents on each one of its four sides the block-letter H, in metal. 30 *c c* are links made of loops, into which or between which the short pieces of square tube are inserted to form the ornamental part of the link or the connection between the links, as

is shown in the different figures of the drawings. 40

Heretofore ornamental chain-links have been ornamented in a variety of ways by sleeves placed over the links or inserted between the links, and square tubes cut into the sides have heretofore been used to so ornament chain-links; but in all such cases the axis of the tube has been on a line with the link. 45

The leading feature of my design consists in the short square tube cut across the ends, so as to represent on the four sides the letter H, 50 and placed at right angles to the links.

A large variety of ornamental chains can be made in which the short tube or letter-H sleeve is combined with chain-links, besides the various forms shown in the drawings. 55

Having thus described my newly-invented design, I claim as new and desire to secure by Letters Patent—

1. The design for ornamental chains herein shown and described, the same consisting in 60 combining with chain-links a short piece of square tubing having the ends cut by cross-cuts, so that each side represents the letter H.

2. The design for ornamental chains herein shown and described, the same consisting in 65 placing short pieces of square tubing, each side of which represents the letter H, within or between the chain-links, with the axis of the tube at right angles to the line of the link, as described.

In witness whereof I have hereunto set my hand.

SIGMUND L. LEDERER.
